Attorney

UNITED STATES PATENT OFFICE

TETSUO TOMONAGA, OF DEAL, NEW JERSEY

CIGAR CASE

Application filed September 19, 1929. Serial No. 393,733.

This invention relates broadly to smokers' appliances, and has more particularly reference to a cigar case.

The primary object of this invention is, therefore, the provision of such a case adapted for receiving partially smoked cigars, of varying lengths, and while still in an ignited state.

A still further object of the invention is 10 the provision of such a case having slidably contained therein an inner receptacle adapted to receive the burning end of a cigar, said inner receptacle adapted to be moved longitudinally of the outer case in order to permit 15 cigars of varying lengths being inserted within said outer case.

A still further object of the invention is to provide a cigar case having slidably mounted therein an inner receptacle for receiving the burning end of a cigar together 20 with retaining means within the outer case for engagement with the cigar to prevent the casual withdrawing of the burning end of the cigar from the inner receptacle.

25 A still further object of the invention is to provide in a cigar case of the character above mentioned, means for preventing casual displacement of the sliding inner receptacle.

30 A still further object of the invention is to provide in a cigar case of the character above mentioned an inner receptacle of such a construction that when the outer case is closed will completely enclose the burning 35 end of a cigar maintaining the same out of contact with the outer casing and at the same time smother the burning end of the cigar contained therein.

A still further object of the invention is 40 to provide within a cigar case an inner receptacle capable of receiving cigars of varying diameters and at the same time insuring a snug fit of the inner receptacle about the burning end of the cigar.

45 Other objects and advantages of the invention will become apparent during a study of the following description, taken in connection with the accompanying drawings, wherein:

50 Figure 1 is a vertical longitudinal sectional

view taken through the device constructed in accordance with the present invention.

Figure 2 is a plan view of the same showing the device in open position and the manner of inserting and retaining a burning 55 cigar therein.

Figure 3 is a rear side elevation of the cigar case.

Figure 4 is a vertical transverse sectional view taken substantially on line 4—4 of Figure 1.

With reference more in detail to the drawings, and wherein like numerals refer to similar parts throughout the several views, it will be seen that the device comprises an outer 65 casing embodying a bottom section 5 of elongated cup-shaped configuration and a top section 6 being also of elongated cup-shaped configuration. The bottom section 5 is rounded at its opposite ends as at 7, and likewise the top section 6 is rounded at its opposite ends as at 8.

In hingedly connecting the sections, I provide on one longitudinal wall of each section adjacent the ends thereof apertured ears 9—9. 75 An elongated hinge rod 10 has its opposite ends extending through the mated ears of the sections thus forming a hinged connection between the sections.

The top section 6 on its other longitudinal wall and at the lower edge thereof is pressed outwardly as at 11 to provide a clamping mouth adapted to receive a spring tongue 12 on the upper edge of the outer longitudinal wall of the section 5 so that when said sections are closed one upon the other the spring tongue 12 will be received into the mouth 11 thus providing a spring catch for the sections to maintain the sections in a closed position.

Arranged within this outer casing is an 90 inner receptacle comprising a pair of complementary sections, one of which sections, 13, is arranged within the upper section 6 of the outer casing, while the other of said sections, 14, is arranged within the lower section of said outer casing. The sections 13 and 14 of the inner receptacle are substantially identical in construction and configuration, and as shown to advantage in Figure 4 each of the sections is substantially semi-circular in cross-sec- 95 100

tion, and each of the sections is open along the top side thereof, closed at one end and open at the opposite end as at 15 and 16, respectively. The sections of the inner container or receptacle are preferably made of a very hard rubberized composition and is lined with asbestos or other similar fire-proof material. At their opened ends the sections 13 and 14 are provided with arcuate inwardly directed flanges 17 and 18, respectively, which flanges are preferably made of rubber in a resilient state in order that the flanges may snugly fit about that end of the cigar inserted within the inner receptacle.

15 The section 14 of the inner receptacle with in the section 5 of the outer casing is pro vided intermediate its ends with a pair of laterally extending co-extensive apertured ears 19—19. The other section 13 of the inner receptacle is provided on one side thereof with a laterally extending apertured ear 20 adapted to extend between the ears 19, and the hinge rod 10 extends through the aligned apertures of the ears 19 and 20 whereupon it 25 will be seen that the sections 13 and 14 re spectively, are slidable upon the rod 10 and in the respective sections of the outer casing.

Secured to the bottom longitudinal wall of the section 13 of said inner receptacle is a 29 spring 21. The spring 21 is anchored intermediate its ends adjacent the opened end of said section 13 as at 22 and one end of said spring extends beyond the said opened end of said section, said one end being bent in wardly and then continued longitudinally as is indicated to advantage at 23. The other end portion of the spring 21 is similarly bent as at 24 so as to frictionally bind against the bottom wall of the top section 6 of the outer 39 casing and the bottom wall of the section 13 of the inner receptacle. A similar spring 25 is likewise anchored intermediate its ends to the inner receptacle section 14 as at 26, and one end of the spring 25 is bent inwardly and then continued longitudinally as at 27, said end extending beyond the opened end of the section 14, while the other end portion of the spring 25 is similarly bent as at 28 so as to bind against the bottom wall of the section 14 and the wall of the section 5 of the outer casing.

Manifestly, the springs 21 and 25 binding against the walls of the respective sections as just described, will prevent casual dis placement of the respective sections 13 and 14 when the sections have been slid longitudinally on the rod 10 to any predetermined position within the respective sections of the outer casing, in order to accommodate a cigar of varying length. Likewise, when the cigar, having been partially smoked as indicated by the reference character C is inserted in the section 14 of the inner receptacle, and the outer casing is then 53 closed the section 13 of the inner receptacle

will then be disposed over the section 14 of the inner receptacle and forming therewith a somewhat cylindrical inner receptacle completely receiving the burning end of the cigar C, while the end portions 23 and 27, respectively of the spring will then engage the cigar C at diametrical opposite sides of the cigar, or at the top and bottom sides of the cigar as is apparent, thus retaining the burning end of the cigar in the section of the inner receptacle.

Of course, the burning cigar C may be inserted in either of the sections 13 or 14 when the case is open, and these sections being opened along their top at one end thereof 80 permit of easy insertion of the burning end of the cigar in one of the sections of the inner receptacle, and likewise facilitate the removal of the cigar from the sections when the outer casing has been opened to permit 85 access to be had to the cigar.

If desired one end of each of the sections 5 and 6 of the outer casing may be lined with imitation ivory or the like, that is at that end wherein would lie the wet or mouth end, 90 of the cigar in order to provide a sanitary bed for the wet end of the cigar.

It is also to be noted that the springs 21 and 25 maintain the sections of the inner receptacle in spaced relation from the wall 95 of the sections of the outer casing providing a clearance space 29 between the sections of the inner receptacle and outer case.

Obviously if the cigar be lighted when inserted in the section of the inner receptacle, and the case is then closed the complementary section of the inner receptacle which will then be disposed over that section first receiving the cigar will securely clamp the cigar between said sections of the inner receptacle and spaced from the walls of the outer case.

The case may be carried about one's pocket in any convenient manner, and will be found especially desirable for smokers since when entering a dwelling, or other places where smoking is prohibited they need not throw away their partially smoked cigars, but rather insert the burning cigar in the casing in the manner hereinbefore fully set forth, wherein it will be soon extinguished, and further, the burning cigar may be inserted in the inner container while there is still ash on the burning end of the cigar, since the inner container or receptacle is also adapted for receiving the ash of the cigar as is ap parent.

It is believed that from the foregoing de scription, taken in connection with the accompanying drawings, a clear understand ing of the construction, utility and advantages of a cigar case of this nature will be had. A more detailed description is therefore deemed unnecessary.

Even though I have herein shown and de

scribed the preferred embodiment of my invention, it is to be understood that the same is susceptible to changes fully coming within the spirit of the invention as herein described, and the scope of the appended claims.

Having thus described my invention, what I wish to claim as new is:—

1. In a device of the class described, the combination of an outer casing and an inner receptacle, said outer casing comprising a cup-shaped bottom section and a cup-shaped top section, said inner receptacle comprising a pair of complementary semi-cylindrical sections, one section of said inner receptacle adapted for position in the bottom section of the outer casing, and the other section of said inner receptacle adapted for position in the top section of said outer casing, hinge means for securing the sections of said outer casing, said hinge means including means for slidably mounting the sections of the inner receptacle in their respective sections of said outer casing.

2. In a device of the class described, the combination of an outer casing and an inner receptacle, said outer casing comprising a cup-shaped bottom section and a cup-shaped top section, said inner receptacle comprising a pair of complementary semi-cylindrical sections one section of said inner receptacle adapted for position in the bottom section of the outer casing, and the other section of said inner receptacle adapted for position in the top section of said outer casing, hinge means for securing the sections of said outer casing, said hinge means including means for slidably mounting the sections of the inner receptacle in their respective sections of said outer casing, spring means carried by the sections of the inner receptacle for frictional engagement with the walls of the sections of the outer casing for retaining the sections of the inner receptacle against casual displacement in their respective sections of said outer casing.

3. In a device of the class described, the combination of an outer casing and an inner receptacle, said outer casing comprising a cup-shaped bottom section and a cup-shaped top section, said inner receptacle comprising a pair of complementary semi-cylindrical sections, one section of said inner receptacle adapted for position in the bottom section of the outer casing, and the other section of said inner receptacle adapted for position in the top section of said outer casing, hinge means for securing the sections of said outer casing, said hinge means including means for slidably mounting the sections of the inner receptacle in their respective sections of said outer casing, spring means carried by the sections of the inner receptacle for frictional engagement with the walls of the sections of the outer casing for retaining the sections of the inner receptacle against casual displacement in their respective sections of said outer casing.

the inner receptacle against casual displacement in their respective sections of said outer casing, and said spring means having end portions extending beyond adjacent ends of the sections of the inner receptacle, the extended ends of said spring means being curved for frictional engagement with an article arranged within said inner receptacle when said inner receptacle and outer casing is disposed in a closed position.

4. A cigar case comprising in combination a relatively elongated outer casing, a relatively short inner receptacle arranged in said outer casing, said inner receptacle adapted to receive therein one end of a cigar, means for slidably mounting said inner receptacle within said outer casing whereby said inner receptacle may be moved longitudinally relative to said outer casing for accommodating cigars of varying length.

5. A cigar case comprising in combination a relatively elongated outer casing, a relatively short inner receptacle arranged in said outer casing, said inner receptacle adapted to receive therein one end of a cigar, means for slidably mounting said inner receptacle within said outer casing whereby said inner receptacle may be moved longitudinally relative to said outer casing for accommodating cigars of varying length, and frictional means for retaining said inner receptacle at a predetermined location in said outer casing against casual displacement.

In testimony whereof I affix my signature.
